INTERNAL COMBUSTION ENGINE

Charles I. McNeil, Bloomfield, N. J., assignor to
 Eclipse Aviation Corporation, East Orange,
 N. J., a corporation of New Jersey

Application April 10, 1936, Serial No. 73,800

2 Claims. (Cl. 60—97)

This invention relates to internal combustion engines and particularly to a plurality of such engines having a tendency to deviate from a desired common speed.

An object of the invention is to provide means for maintaining one or more internal combustion engines at predetermined relative speeds.

A second object of the invention is to provide in a system which includes a master engine and one or more additional engines, means responsive to the rotation of said master engine to produce corresponding rotation of each of said additional engines. In this connection a feature of the invention is the provision of a motion differential device operating to vary the speed of each additional engine in accordance with and in response to any variations in the speed of the master engine.

These and other objects and features of the invention will become apparent upon consideration of the following detailed description, and upon reference to the accompanying drawing illustrating the preferred embodiment of the invention. It is to be understood, however, that the drawing is illustrative only, and is not intended as a definition of the limits of the invention, reference being had to the appended claims for such a definition of limits.

In the drawing the invention is shown schematically as applied to a master engine 5 and one additional engine 6, a showing of other additional engines being considered unnecessary as it will be evident from the following description how the invention is to be applied to such other additional engines to control said other engines in the manner in which the engine 6 is herein shown controlled.

Each engine is shown equipped with reduction gearing 11, 12 to cause rotation of cams 13, 14, respectively, at rates proportional to the speeds of the driving engines. The cams operate circuit closing switches 16, 17, and 18 to periodically connect the source 19 with the transformer primaries 21, 22 and 23, respectively, having secondaries 24, 25 and 26 associated therewith, the windings 24 and 25 being "Scott connected" as indicated at 27 and 28 to provide currents one hundred twenty degrees out of phase in the three sections 31, 32 and 33 of the three phase stator winding of alternating current motor 34. Rotor winding 36 of motor 34 is in circuit with the secondary winding 26 of the transformer whose primary circuit pulsations are controlled by switch 18 of engine 6.

Due to the quadruple and offset lobe formation 55 of cam 13, as contrasted with the double lobe

formation of cam 14, the currents pulsating through the primaries 21, 22 will be ninety degrees out of phase with each other; and they will also produce—due to the Scott connections 27, 28—conventional three phase alternating current in the stator windings 31, 32, 33, the frequency of which will correspond exactly to the frequency of the pulsations of current through rotor winding 36—assuming the two engines to be operating at synchronous speeds.

Should the speed of engine 6 deviate from that of engine 5, there will be a resulting difference in frequency between the magnetic (torque producing) "peaks" produced by the windings 31, 32, 33 on the one hand, and those of the winding 36, 15 and hence a departure from the normal, self-canceling torque reactions. The result will be a turning of the rotor until the resultant shifting of throttle valve 37 alters the fuel consumption of engine 6 sufficiently to restore the latter to synchronization with master engine 5.

What I claim is:

1. A synchronizer for the propellers of a multi-engine aircraft having at least two engines, each equipped with a transformer and each constituting the driving means for one of the propellers, said synchronizer including, in addition to said transformers, means for sending pulsating current through the primaries of said transformers, means for inductively associating the secondary currents of said transformers whereby there is produced electromagnetically a rotational movement through an arc of length varying in proportion to the difference in speeds of the two engines, a throttle controlling fuel admission to one of said engines, and means for translating said rotational movement into a shifting of said throttle, to an extent proportional to the arc of the rotational movement.

2. Means for synchronizing the speeds of two engines, one of which is equipped with a combustion regulator and each of which is equipped with an engine driven periodic circuit interrupter, said means comprising a dynamo electric machine, a pair of transformers subject to said interrupters, 45 a current source for the primaries of said transformers, means for sending the currents generated in the secondaries of said transformers through the stator and rotor, respectively, of said dynamo electric machine, to produce movement 50 of the rotor of said machine in proportion to the degree of asynchronism between said engines, and means for causing said movement to take effect upon said combustion regulator.

CHARLES I. MCNEIL. 55
